(57) **CLAIM**

The ornamental design for an automotive emergency strobe light, as shown and described.

DESCRIPTION

FIG. 1 is a front perspective view of an automotive emergency strobe light showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the automotive emergency strobe light;

FIG. 10 is an enlarged view of portion 10 shown in FIG. 1; and,

FIG. 11 is an enlarged view of portion 11 shown in FIG. 5. The broken lines indicate cutoff boundaries for enlarged detail portion views and form no part of the claim.

1 Claim, 11 Drawing Sheets
